DESIGN FOR A DECORATIVE ALPHABET FOR FORMING MONOGRAMS FOR WEAR- ING APPAREL OR SIMILAR ARTICLE

Charles Emmey, New York, N. Y.

Application March 5, 1936, Serial No. 61,484

Term of patent 7 years

To all whom it may concern:

Be it known that I, Charles Emmey, a citizen of the United States, residing in the city and county of New York, State of New York, have invented a new, original, and ornamental Design for a Decorative Alphabet for Forming Monograms for Wearing Apparel or Similar Article, of which the following is a specification, reference being had to the accompanying drawing, forming part thereof.

The drawing shows a plan view of a decorative alphabet for use in connection with wearing apparel, or similar article. Each letter is characterized by having its ending component parts joined at sharp angles.

The letters forming the present design are of no appreciable thickness.

I claim:

The ornamental design for a decorative alphabet for forming monograms for wearing apparel or similar article, as shown and described.

CHARLES EMMEY.
